UNITED STATES PATENT OFFICE.

HENRY HEATH, OF NEW YORK, N. Y., ASSIGNOR TO FISK, CLARK & FLAGG,
OF SAME PLACE.

DESIGN FOR A SCARF.

SPECIFICATION forming part of Design No. 13,031, dated July 11, 1882.

Application filed March 22, 1882. Term of patent 7 years.

To all whom it may concern:

Be it known that I, HENRY HEATH, a subject of the Queen of Great Britain, residing in the city, county, and State of New York, have invented and produced a new and original Design for Scarfs, of which the following is a full, clear, and exact description thereof, reference being had to the accompanying drawings, and to the letters of reference marked thereon, making a part of this specification.

Figure 1 is a side elevation of my newly-designed puffed or knotted "Claudent" scarf, Fig. 2 being an edge view thereof from the side, and Fig. 3 a similar view from the top thereof.

My design relates to Claudent scarfs for men's wear—that is to say, to comparatively-wide made-up scarfs formed with crossed aprons having elliptically-curved upper outer edges.

The leading feature of my design consists in a puffed or outwardly-curved projecting surface at the upper portion of the scarf broken by parallel depressed lines which, starting each at the top of either apron at or near the intersection of its inner edge with the top or neck line of the scarf, extends thence down the apron at a right angle with said neck-line, and is lost in the puffed surface at or about the apex thereof below the point of intersection of the inner edges of the two aprons.

A A are the crossed aprons, whose upper outer edges are crossed, and which intersect, as shown in Fig. 1. B is the neckband. C is the center piece of the scarf, whose upper edge, uniting with the upper edges of the aprons, forms the neck-line or top line of the scarf.

The aprons A A are puffed or pushed outwardly in the upper portion thereof, so as to present (when the scarf is viewed edgewise, with its under side laid against a flat plane surface represented by the line $x x$ in Figs. 2 and 3) an outwardly-curved or conical outline, which, starting from the upper outer edge of the scarf at a, Fig. 2, gradually inclines to an apex at b about on a line with the intersection of the two aprons, and thence falls away more abruptly from b to c toward the lower end of the scarf, and from c to d continues in right line, substantially as shown in the draw-

ings, Fig. 2. When viewed edgewise from the top of the scarf the surface of the scarf presents an outline, which, as shown in Fig. 3, starting at e on one edge of the scarf at the point of its greatest width inclines upwardly outwardly to the point b at about one-third of the width of the scarf, (more or less,) then extends in a direction about parallel with the plane $x x$ and in a line more or less even for a distance about equal to one-third the width of the scarf to a point, b' , and thence at an incline to the level of the edge of the scarf at the point e' . Two parallel lines, $fb, f' b'$, are formed on the upper portion of the scarf, beginning, as shown in Fig. 1, from points ff' on the $x x$ line at about the intersection of the inner edges of the aprons with said neck-line, and which, extending at about a right angle with the general direction of said neck-line toward the center of the apron, terminate and are lost at the elevated points $b b'$ in the puffed surface of the aprons. The surface of the quadrangular space embraced within or between these lines is depressed and is broken by the lines of the inner edges of the aprons intersecting over the center piece, C, as is shown in the elevation, Fig. 1.

I do not claim as new either the curved outline of the scarf when viewed in either direction edgewise, nor the curved outlines of the upper outer edges of the aprons as seen in the elevation.

I claim—

The design for a puffed scarf, consisting of the depressed parallel lines $fb, f' b'$, which, beginning each at or about the intersection of the inner edge of the aprons with the neck-line of the scarf, extend thence at about a right angle with the general direction of said neck-line and terminate at the points $b b'$ at the apex of the puffed surface of each apron, as herein shown and described.

In testimony whereof I have signed my name to this specification in the presence of two subscribing witnesses.

HENRY HEATH.
